FOREIGN PATENT DOCUMENTS

JP 2013-56114 A 3/2013

Primary Examiner — David G Muller*(74) Attorney, Agent, or Firm* — Brinks Gilson & Lione(57) **CLAIM**

We claim the ornamental design for a medical tube holder, as shown and described.

DESCRIPTION

FIG. 1 is a front view of a medical tube holder of the present invention, with two pairs of claws shown in a closed position;

FIG. 2 is a rear view thereof;

FIG. 3 is a plain view thereof;

FIG. 4 is a bottom view thereof;

FIG. 5 is a left side view thereof;

FIG. 6 is a right side view thereof;

FIG. 7 is a perspective view thereof;

FIG. 8 is a front view of the medical tube holder of the present invention, with the two pairs of claws shown in an open position;

FIG. 9 is a rear view thereof;

FIG. 10 is a plain view thereof;

FIG. 11 is a bottom view thereof;

FIG. 12 is a left side view thereof;

FIG. 13 is a right side view thereof; and,

FIG. 14 is a perspective view thereof.

The broken line showing of parts of the drawings is included for the purpose of illustrating use and environment and forms no part of the claimed design.

1 Claim, 14 Drawing Sheets(56)
